UNITED STATES PATENT OFFICE.

AARON E. SWANBERG, OF CASS LAKE, MINNESOTA.

PLANTER.

1,280,329.

Specification of Letters Patent.

Patented Oct. 1, 1918.

Application filed February 16, 1918. Serial No. 217,609.

To all whom it may concern:

Be it known that I, AARON E. SWANBERG, a citizen of the United States, residing at Cass Lake, in the county of Cass and State 5 of Minnesota, have invented new and useful Improvements in Planters, of which the following is a specification.

This invention relates to hand planters and it consists in the novel features herein- 10 after described and claimed.

An object of the invention is to provide a planter of the character stated which is especially adapted to be used for depositing seed in the soil although the implement 15 may be used to advantage for forming an opening or pocket in the soil in which propagated plants may be placed when the same are set out in a field or patch.

With this object in view the planter comprises a casing having a conical end portion and an angular flange located at a point between its ends. The said casing is hollow and is closed at one end by means of a cap. A rod is slidably mounted in the cap and 20 traverses the length of the casing and is provided at its lower end with a cone shaped head adapted to normally close the lower end of the casing. A pin is mounted upon the cap and a knob is screw threaded there- 25 on. A washer is mounted upon the rod and interposed between the knob and the pin and a spring bears at one end against the washer and at its other end against the cap and is under tension with a tendency to 30 hold the knob away from the pin and the head which is carried by the rod against the lower end of the casing.

In the accompanying drawings:—

Figure 1 is a side elevation of the planter; 40 Fig. 2 is a vertical longitudinal sectional view of the same.

The planter includes a casing 1 which is hollow and the said casing is provided at its lower end with a cone shaped portion 2. 45 At the upper end of the cone shaped portion 2, the casing 1 is provided with an angular flange 3. A cap 4 normally closes the upper end of the casing 1 and a rod 5 is slidably mounted in the cap 4 and traverses the 50 length of the casing 1. The rod 5 carries at its lower end a cone shaped head 6 which normally closes the lower end of the casing 1 as hereinafter described. A pin 7 is mounted upon the cap 4. A knob 8 is screw threaded upon the upper end of the rod 5 and by turning the said knob it may be ad-

justed in position upon the rod. A washer 9 is mounted upon the rod 5 and the lower face of the knob 8 bears against the upper surface of the said washer. The pin 7 is located in the path of movement of the washer 9. A spring 10 is interposed between the upper surface of the cap 4 and the lower surface of the washer 9 and the said spring is under tension with a tendency to hold the washer 9 away from the upper end of the pin 7 and to hold the rod 5 in a position whereby the head 6 is held in a closed position against the lower end of the casing 1. The casing 1 is preferably formed from 70 wood and the head 6 is preferably made of hardened steel or similar material.

When the implement is used for forming a pocket or opening in the ground for the reception of a propagated plant the head 6 remains in a closed position against the lower end of the casing 1 and the conical portion of the said casing together with the head 6 is inserted in the soil until the flange 3 comes in contact with the surface of the 80 soil. The implement is then withdrawn from the soil thus leaving a pocket or opening therein in which may be deposited a plant and the soil may be crushed or deposited about the roots of the plant thus accomplishing the planting operation.

When the implement is used for depositing seed in the ground the cap 4 is removed and the seed is spilled into the casing 1. The knob 8 is then adjusted upon the rod 5 to 90 regulate the movement of the said rod with relation to the casing when the knob is depressed. The lower portion of the casing is then inserted in the soil as hereinbefore described and when the flange 3 comes in 95 contact with the surface of the soil the knob 8 is depressed whereby the rod 5 is moved longitudinally and this movement is limited by the washer 9 coming in contact with the upper end of the pin 7. As a result of the movement of the rod 5 the head 6 is moved away from the lower end of the casing 1 and hence the lower end of the said casing is opened and the seed may gravitate from the casing into the opening or pocket which 100 has been formed in the soil.

When pressure is removed from the knob 8 the rod 5 is moved in an upward direction through the casing 1 and the head 6 is brought to a closed position against the 110 lower end of the said casing. The said casing is then removed from the soil and the

seed which has been deposited in the soil is covered by pressing down the sides of the opening or pocket which has been previously formed and thus the planting operation is completed.

It is apparent that by adjusting the knob 8 upon the rod 5 the extent of movement of the rod 5 with relation to the casing 1 may be regulated and consequently the head 6 10 may be moved for a greater or less extent away from the lower end of the casing and hence the quantity of seed which is deposited in the soil may be regulated.

From the foregoing description taken in conjunction with the accompanying drawing, it will be seen that a planter of simple and durable structure is provided and that the same may be used to advantage for forming pockets in the soil for propagating

plants and also for depositing seed in the soil.

Having described the invention what is claimed is:

A planter comprising a casing which is hollow throughout its length, a cap detachably mounted upon the casing, a rod slidably mounted in the cap and traversing the length of the casing, a head carried by the rod and adapted to close one end of the casing, a pin mounted upon the cap, a knob adjustably mounted upon the rod, a washer interposed between the knob and the pin and a spring engaging the cap and adapted to normally hold the head in engagement with the end of the casing.

In testimony whereof I affix my signature.

AARON E. SWANBERG.
